UNITED STATES PATENT OFFICE.

ERIC MOARD, OF EAST HAMPTON, CONNECTICUT, ASSIGNOR TO BEVIN BROTHERS MANUFACTURING COMPANY, OF EAST HAMPTON, CONNECTICUT, A CORPORATION OF CONNECTICUT.

SIGNALING DEVICE.

1,332,991.

Specification of Letters Patent.

Patented Mar. 9, 1920.

Application filed April 25, 1918. Serial No. 230,629.

To all whom it may concern:

Be it known that I, ERIC MOARD, a citizen of the United States, and a resident of East Hampton, in the county of Middlesex and State of Connecticut, have invented 5 certain new and useful Improvements in Signaling Devices, of which the following is a full, clear, and exact description, whereby any one skilled in the art may 10 make and use the same.

The invention relates to signaling devices, horns or alarms wherein the sound is produced through a vibratory diaphragm that is mechanically agitated.

15 It relates more particularly to refinements of such a device through which a very efficient signaling device may be produced at a minimum cost and with very light, though substantial, construction.

20 Difficulty has been experienced in attempting to make small horns for bicycles and the like which would emit a sufficiently sharp and distinctive tone, although the same principles of operation have been successfully applied in larger structures.

25 It is, therefore, one of the objects of the present invention to simplify the construction of such a device so far as possible and to provide for tone qualities.

30 Referring to the drawings:

Figure 1 is a plan view of the device as applied to the handle of a vehicle.

Fig. 2 is a view in side elevation.

35 Fig. 3 is a sectional view with the top plate removed.

Fig. 4 is a rear view of the sound chamber and appurtenant parts.

Fig. 5 is a fragmentary view of the cam plate.

40 In a device of this sort, it has been a common practice to flex a diaphragm by rotating a cam having teeth which would impinge upon and move a contact or anvil member centrally secured to the diaphragm.

In such devices, ordinarily, the diameter of the cam member has been comparatively small; and reliance has been placed upon giving it an amplified rotary movement 45 through a gearing in order to speed it up to give the required number of vibrations to the anvil.

50 This has required a somewhat complicated mechanism, involving gearing and

necessitating considerable effort or pressure 55 upon the driving gears.

Ordinarily, in such devices, the cam member rotates in the same direction and there is a ratchet or releasing device between it and the operating train and a weighted 60 member for giving a fly-wheel effect to the cam.

The present invention contemplates a very compact and very light structure in which the cam-wheel or vibrating member 65 has an oscillatory movement and is of comparatively large diameter, so that its backward and forward movements will produce a sufficient speed of vibration and sufficient amplitude of movement for the diaphragm 70 to take advantage of its high-pitched tones.

In the accompanying drawings, the numeral 1, denotes the front plate which is centrally perforated as at 2, to receive the amplifying horn or mouth piece 3. The 75 plate is struck up from sheet metal and is provided with securing means such as tangs 4, which are swaged through openings 5, formed in the peripheral edge of a cooperating casing member 6. Between the member 1, and member 6, is clamped the diaphragm 7, which has an anvil or striker-piece 8, centrally arranged therein and made adjustable.

The casing member 6, is drawn out as at 85 6^a, to provide a sound chamber 9, which is closed by a plate 10, except for a slot 11, of sufficient size to permit the cam plate 12, to project therethrough. To the rear of this casing 6, is secured a casing 13, consisting 90 of a plate 14, and a rectangular box-like member 15. The plate is scarfed at various points as at 16, and tangs 17, are forced over the edge of the plate to hold the parts together, thus forming a rectangular box for 95 containing the driving mechanism. This box is secured to the rear wall of the casing 6, by ears 18.

Projecting through the casing 13, is a stud 19, upon which is mounted the actuating 100 wheel or cam 12. This cam has secured to it a pinion 20, which meshes with a segmental gear 21, pivoted on a stud 22, and actuated by a thumb-bar 23, which extends through an opening in the casing 13, and is pivoted 105 to the gear segment as at 24. A spring 25, normally holds the segment and thumb-bar 23, at one limit of its play.

The actuating gear 12, is cupped up from sheet metal, as illustrated, and its flanged edge 12^a, is then crimped to form the necessary serrations to impinge upon and actuate the diaphragm 7. The member 12, may, of course, be case-hardened after it is crimped and thus give a substantially non-wearing actuator.

The casing 13, is provided with a suitable clamp 26, by which it may be secured in place.

The operation of the device is quite obvious. As the bar 23, is depressed, the segment 21, meshing with the pinion 20, rotates the member 12, with rapidity, causing a vibration of the diaphragm 7. A quick release of the bar 23, permits the spring to retract the gear segment 21, whereupon a further vibration is imparted to the diaphragm. With the actuating member 12, of comparatively large diameter, a very high degree of vibration may be imparted to the diaphragm, and, as the diaphragm is arranged in the closed metallic chamber 9, a tone of unusual brilliancy is secured.

It will be observed that all parts of the device may be formed from light metal, stamped to form, and that the flat push bar 23, resting against the plate 14, obviates the necessity of complicated guides and connections for rotating the member 12.

The member 20, may be given a maximum diameter relative to the size of the casing used, and it will be obvious that a great number of teeth may thus be brought into contact with the anvil during a single movement of the push bar 23.

In forming this member, it is cupped up from sheet metal in suitable dies and its edge 40 is then crimped in a die to give the proper and exact conformation of cam surfaces or teeth. These, of course, being formed on an annular ring, give greater vibratory reaction than those cut from a solid bar and, apparently, the pitch and tone of the device are enhanced by this form of actuating cam.

Comparisons of this form of device with a form in which the teeth were cut in the peripheral edge of the plate showed pronounced advantage, with all of the other elements of the same form, construction, and size.

No over-running is necessary, as the parts are so light that they may be easily set in motion by the leverage afforded between the point of engagement of the push bar, the pivot point of the segment, and its geared connection to the actuator or cam plate.

The large diameter of the cam plate, which 60 may be substantially equal to the diameter of the sound chamber, permits the use of a comparatively long face on the segmental gear. It follows that with this construction a single depression of the bar 23, and immediate retraction thereof under the action of

the spring, gives a signal of considerable duration, even with a linear movement of the actuator bar of less than an inch.

A notable advantage in the arrangement resides in the ability to adjust the anvil 70 so that it will closely follow the peripheral curves or cams of the actuator. This obviates the sharp metallic striking effect so commonly found in horns, due to the hammer-blow or impact of the teeth upon the 75 anvil, in contra-distinction to the rapid vibration of the diaphragm, by causing the anvil to follow the curves of the actuator as herein defined.

What I claim as my invention and desire 80 to secure by Letters Patent is:

1. In a signaling device, a two part casing, a diaphragm secured between the casings, a separable rectangular casing forming a support for and with its contained actuating mechanism providing a complete removable unit, an actuating mechanism mounted in the removable casing, an actuator cam forming a part of said unit actuating mechanism, said cam mounted in and projecting 85 beyond the separable rectangular casing and into the casing supporting the diaphragm.

2. In a signaling device, a two part casing comprising a front plate and a casing forming a sound chamber, a diaphragm clamped between said casings and provided with an adjustable anvil extending through the diaphragm, a separable rectangular casing providing a support for and inclosing a 90 unit actuating mechanism for the diaphragm, said casing being removably secured to the casing of the sound chamber, an actuating mechanism mounted in the rectangular casing bodily removable therewith and 95 having a cam projecting beyond the casing and into the sound chamber to vibrate the diaphragm as it impinges against the adjustable anvil, and means for moving said cam.

3. In combination with a cylindrical casing forming a sound chamber, a diaphragm operatively supported with reference thereto, an adjustable anvil extending through the diaphragm, an actuating mechanism 115 mounted in a separable rectangular casing and forming a unit actuating mechanism, said mechanism including a cam with its working face projecting beyond the casing to engage the anvil, to actuate the diaphragm, a 120 slot in the sound casing through which said cam projects, and means for oscillating said cam.

4. In a signaling device, a sound chamber inclosed by a casing having a flange and 125 cylindrical body-part, a diaphragm resting against the flange, a cover plate for the diaphragm having tangs engaging and overlapping the flange and providing a clamping means for the casing, cover, and diaphragm; 130

and an actuating mechanism for the diaphragm supported in a casing attached to the sound casing and forming therewith a complete unit actuating mechanism and having an actuating cam projecting into the sound chamber to vibrate the diaphragm, and an adjustable anvil extending through the diaphragm to be engaged by the cam.

5. In a signaling device, a sound chamber 10 casing, a diaphragm clamped thereto, an adjustable anvil extending through the diaphragm, a casing for an actuating mechanism of rectangular form removably secured to the sound chamber casing, an oscillatory 15 rotary cam member supported in the rectangular casing and projecting therefrom to engage the anvil of the diaphragm, a gear segment pivoted in said rectangular casing and engaging a pinion, said pinion adapted 20 to rotate with and oscillate the cam, an actuating plunger pivoted to said gear segment, and resilient means for holding said gear segment at one limit of its play.

6. The combination in a signaling device 25 having a main sound chamber casing, operating mechanism for flexing a diaphragm through engagement with its anvil, and a diaphragm to be held against one side of said casing and provided with an adjustable anvil passing therethrough; of a cover plate 30 for the diaphragm having tangs adapted to be swaged over the edge of the casing,

whereby the said diaphragm is permanently clamped with respect to the casing.

7. The combination in a signaling device 35 having a main sound chamber casing, operating mechanism for flexing a diaphragm through engagement with its anvil, and a diaphragm to be held against one side of said casing and provided with an adjustable anvil 40 passing therethrough, said casing having openings to receive tangs; of a cover plate for the diaphragm having tangs adapted to be swaged into the openings of the casing, whereby the said diaphragm is clamped 45 and relative rotation of the cover plate and casing is prevented with respect to the casing.

8. The combination in a signaling device 50 having a vibratory diaphragm and mechanism for actuating a cam for flexing said diaphragm; of an actuating cam comprising a disk having an annular flange arranged at right angles to the plane of the disk, said flange crimped to provide undulating cam surfaces.

9. An actuating cam for vibratory diaphragms comprising a disk having a stamped up annular flange arranged at right angles to the plane of the disk and crimped to provide undulating cam surfaces.
